WEAVER'S LOOM

Harald Andersen Lervad, Askov, Vejen,
Denmark

Application June 15, 1937, Serial No. 148,379

1 Claim. (Cl. 139—33)

The present invention relates to a loom, the advantage of which is that it is constructed of only a few parts, which can be assembled in a minute by anybody, so that, when not in use, it occupies 5 but very little space. Furthermore, the construction of the loom is simplified to such degree that everybody can learn to work it in a very short time. This is due to the very simple principle of the loom, which is so constructed that 10 three functions, i. e., adjustment of the width of the warp in the course of rolling-up on the beam, change of the partition, and, finally, the leashing of the threads into cloth, which in a treadle-loom are effected by means of three individual parts of the loom, that is the raddle, the heddles, and the swing frame with the reed, are 15 in the present loom effected by one tool only, namely the loose raddle, which is made in different finenesses, accordingly as the cloth is to 20 be coarser or finer.

The drawing shows:

Fig. 1 a loom according to the invention in top-view,

Fig. 2 the same in side-view with some hand 25 wheels removed,

Fig. 3 a section on the line 3—3 in Fig. 1,

Fig. 4 part of a raddle,

Fig. 5 a cross-section of a roller, called a beam.

The Figs. 4 and 5 are drawn to a larger scale 30 than the other figures.

1 and 2 are uniform sidepieces, interjoined with a cross-piece 3 by means of bolts with winged nuts 4. In each end of the side-pieces there are bearings 5 and 6 respectively. In the bearings 5 35 a roller 7, serving as a warp beam, is rotatably mounted. In the bearings 6 a rotatable roller 15, serving as a cloth beam, is likewise mounted. An upright support 20 is fixed on each of the side-pieces 1 and 2 by means of a bolt with winged nut 40 22 which is movable in a slit 21 in the side-pieces 1 and 2. In the supports 20, in which are made three notches 23, 24 and 25 a raddle with its upper list 10 is placed in the center notch 24 when beaming the loom. On the ends of this 45 raddle are arranged two balls 28, serving as handles. The raddle consists of a lattice, the connected ends of which are fixed in the upper list 10 and the lower list 26. The lattice consists of a series of equally wide lattice bars 11, 50 each containing a hole with rounded edges 12. Every second of the warp threads are carried through an interspace 13 between the lattice bars 11, whereas every other thread is carried through a corresponding hole 12. When in 55 this way the threads have been carried through

the raddle the width of the cloth to be made, the foremost ends are knitted together in pairs and hooked in the notches 8' on teeth 8, which are arranged in the warp beam 7, after which against either side of the teeth 8 stretching pieces 9 are 5 placed, and secured by screws 9'. The stretching pieces 9 serve to form an even underlayer for the warp threads, which are rolled on the warp beam 7, while the raddle acts in its first function as a raddle, dividing in the course of rolling-up the 10 warp threads evenly on the beam in the width of the cloth to be made. After this the hindmost ends of the warp threads are tied together in pairs and hooked on to the teeth of the cloth beam 15, and the stretching pieces 16 are placed 15 on either side of the teeth 14. Now the shed or partition in the warps is formed by grasping the balls on the upper lists of the raddle and placing them in the topmost notch 25. Thereby the threads, which pass through the holes 12 of the 20 raddle 10, are raised to the uppermost position, thus forming a shed through the threads which pass through the interspaces of the raddle 13. The opposite shed is formed by placing the upper 25 list of the raddle in the lowest notches 23, by which the threads through the holes 12 again form a shed through the threads which pass through the interspaces of the raddle 13. From 30 this it appears that the threads passing through the interspaces of the raddle 13 always remain 35 standing in the same position, whereas the threads passing the holes of the raddle 10 are moved alternately up and down, thereby forming the shed necessary for the weaving. Thereby the raddle exercises its function, replacing the 40 heddles necessary in the treadle-looms. Through the consecutively formed sheds the weft, also called the shoot, is carried by means of the shuttle, and every time this is done the balls on the upper list of the raddle are grasped, and the 45 shoot is pushed forward by the raddle. Thereby the raddle exercises its third function, acting in the same way as the swing frame with the reed of the treadle-looms. To produce the necessary 50 tightening of the warp in the course of weaving, ratchet wheels 17 are fixed to the warp beam 7 and the cloth beam 15, with which some rotatable pawls 18, arranged on the sidepieces 1 and 2, can 55 cooperate. On the warp beam 7 and the cloth beam 15 hand wheels 19 are placed outside the ratchet wheels 17, by means of which the warp beam can be rotated. Gradually as the weaving proceeds, the warp is rolled off the warp beam 7, and the finished cloth is rolled on the cloth beam 15.

I claim:

A loom comprising a frame having a pair of longitudinal side members, bearings supported at the ends of said side members, a warp beam roller mounted in the bearings at one end of the frame, said warp beam roller having a series of teeth adapted to receive the ends of the warp threads to be rolled on said beam prior to weaving, a cloth beam roller mounted in the bearings at the other end of the frame adapted to receive the cloth to be woven, a combined raddle heddle and swing frame positioned between said warp and cloth beams, said combined raddle heddle and swing frame comprising a lattice frame having a plurality of alternate vertical slots through which alternate warp threads are passed and vertical bars each having an intermediate hole through

which the other warp threads are passed, each side of the frame having a longitudinal slot formed therein, an upright support slidably adjustably carried by the slot in each side of the frame and each support provided with a series of three vertically spaced notches, a supporting rod carried by the upper portion of said lattice frame and adapted to be positioned in the intermediate series of notches for threading said loom, in the upper series for raising the warp threads 10 passing through the holes in said bars and in the lower series for lowering the warp threads passing through the holes in said bars, and means for securing said upright supports in adjusted positions. 15
